UNITED STATES PATENT OFFICE.

JAMES STONE, OF AURORA, ILLINOIS, ASSIGNOR OF TWO-THIRDS TO ALICE M. BALL, OF SAME PLACE, AND ELIZABETH FLORSHEIM, OF CHICAGO, ILLINOIS.

CORSET-LACING.

SPECIFICATION forming part of Letters Patent No. 469,412, dated February 28, 1892.

Application filed January 28, 1889. Serial No. 297,841. (No model.)

To all whom it may concern:

Be it known that I, JAMES STONE, of Aurora, in the county of Kane and State of Illinois, have invented certain new and useful 5 Improvements in Corset-Lacings; and I do hereby declare that the following is a full, clear, and exact description thereof, reference being had to the accompanying drawings, and to the letters of reference marked thereon, 10 which form a part of this specification.

This invention relates to that class of lacing-eyes for corsets and similar articles wherein a looped cord or braid forms the lacing-holes or eyelets.

15 The invention embraces the feature of a marginal part of or upon the corset containing lacing-holes which coincide with the loops of the cord or braid.

In the accompanying drawings, Figure 1 is 20 an elevation of the margin of a corset having an overlying part broken away to reveal the construction of the parts. Fig. 2 is a fragmentary view of an eyelet-strip detached and partly made. Fig. 3 is a sectional view of the 25 eyelet-strip shown in Fig. 2. Fig. 4 is a sectional view in the line 4 4 of Fig. 1, illustrating the relation of the eyelet-strip to the adjacent parts when applied in a corset.

A represents a strip of cloth folded upon 30 itself at a , forming, as shown, the two folds a' a'' . The overfolded portions are gummed or pasted together, and near the edge a are punched a series of lacing holes or eyelets a^4 a^4 .

35 a^3 is a cord inserted within the folded edge a of the strip A.

B is a narrow flat braid, or it may be a cord. If a cord, it is loosely woven, so as to be easily flattened. This braid or cord B is 40 pasted or stitched upon the surface of the overfolded portion a^2 in a series of loops b , extending around the holes a^4 and reaching back a considerable distance—as, for example, to the edge of the overfolded part a^2 , as 45 shown. The loops are unattached to the overfolded portion a^2 at the part adjacent to the holes a^4 , by which arrangement they may be easily and cheaply constructed, any sewing lengthwise of the cord or around the holes 50 being rendered unnecessary. Desirably the loops are brought together or nearly together

at their inner ends, and the cord extended from one loop to the next in a substantially straight line, also as shown, in order to give a smoother surface to the finished article. 55 Whether stitched or gummed in place, the braid or cord B is flattened down as much as practicable, except at the eyelets a^4 . Before applying the cord or braid the folded strip is desirably stitched near the edge a . 60

The eyelet-strip A is complete, as above described. In applying the strip A to a corset its inner edge a' is placed beneath the edge of the marginal section C of the corset in the usual manner. Upon the opposite or upper 65 side of the corset-section C is placed a second strip D, the raw edges of which are turned under, and the inner folded edge of which is opposite the inner folded edge of the eyelet-strip A. The strip D is of proper width to bring 70 its outer edge a short distance inside the eyelet-holes a^4 , and it therefore covers the cord or braid B, excepting at the extreme ends of the loops which surround the said eyelet-holes. The strip D is secured in place by rows of 75 stitching d and d' at its edges, which pass not only through the corset-section C, but also through the inner and folded-in edge and through the body of the eyelet-strip A, as clearly shown in Fig. 4. The one or more 80 rows of stitching d' at the outer margin of the strip D confine the loops b in place and take or share the immediate strain of the lacing-strings when the latter are applied to the corset. A third row of stitching d^2 is desirably inserted at the inner ends of the loops or at a suitable distance from the rows of 85 stitching d' to admit the stiffening-strip E, which is inserted in the usual manner after the rows of stitching have been formed. In 90 this construction the cord or braid forming the eyelet-loops is outside the edge of the double-thick corset-section C, and the completed garment is flat and thin and has an even smooth appearance. It is not, however, 95 strictly essential that the braid should have this precise relation to the edge of the corset-strip C, though it is desirable that it should.

The essential feature of the invention is the combination of a marginal part of the 100 corset containing lacing-holes with the loops b extending around the holes, so that the lac-

ing-strings pass through the lacing-holes, as well as through the loops, said loops being free from the corset at the part adjacent to the holes, but secured thereto at other points. 5 By this means the tension of the lacing is taken both by the cloth of the corset and by the loops, so that less strain is brought upon the loops. By this construction, also, the chafing or wear of the lacings is brought partially on the cloth, so that the loops are not so liable to be rapidly cut through or worn out as when the loops alone are engaged by the lacings.

As far as the main feature of my invention 15 is concerned, the loops may be attached to the corset-body and the lacing-holes or eyelets formed in the marginal part thereof in any manner found convenient or desirable. The particular construction herein shown, however, wherein said lacing holes or eyelets are 20 formed in a separate strip extending beyond the main layers of the corset-body, is of especial advantage in practice, and a construction embracing these last-mentioned features 25 is herein also claimed as a specific improvement.

The cord a^3 serves the purpose of stiffening and giving greater strength to the margin of the corset outside of the lacing-holes, 30 so that the lacings are much less likely to wear or cut through the margin than when such cord is absent and the corset is rendered much more durable. By reason of these advantages the corset provided with a marginal cord arranged in the manner described is 35 herein specifically claimed as a separate improvement.

I claim as my invention—

1. The combination, with a corset provided 40 with lacing-holes in its margin, of cord loops attached to the corset and extending around the said lacing-holes, said loops coinciding with the outer margins of the lacing-holes and being free from the corset in their parts 45 adjacent to the holes, substantially as described.

2. The combination, with the cloth layers forming the main part or body of a corset, of a strip provided with lacing-holes and secured 50 to the body-layers with its edge extending

beyond the margin of the same, and loops secured between the strip and body-layers by stitching and extending beyond the body-layers and around the holes, said loops coinciding with the outer margins of the lacing-holes 55 and being free from the corset in their parts outside of the body-layers, substantially as described.

3. The combination, with the cloth layers forming the main part or body of a corset, of a strip provided with lacing-holes and secured to the body-layers with its edge containing the holes extending beyond the edge of the same, and loops consisting of a continuous 60 looped cord secured by stitching between the strip and the body-layers, with the loops extending around the holes, said loops coinciding with the outer margins of the lacing-holes and being free from the corset in their parts adjacent to the holes, substantially as 65 described.

4. The combination, with a corset having a series of lacing-holes near its edge and provided with a cord stitched into the said edge, of a series of cord loops secured to the corset 75 and extending around the said holes, said loops coinciding with the outer margins of the lacing-holes and being free from the corset in their parts adjacent to the holes, substantially as 80 described.

5. The combination, with the cloth layers forming the body of a corset, of a strip provided with a cord in its outer edge and a series of lacing-holes near the cord, said strip being secured to the body-layers with its edge 85 extending beyond the margin of the same, and a series of cord loops secured by stitching between the strip and body-layers and extending around the lacing-holes, said loops coinciding with the outer margins of the lacing-holes and being free from the corset in their parts adjacent to the holes, substantially as 90 described.

In testimony that I claim the foregoing as my invention I affix my signature in presence 95 of two witnesses.

JAMES STONE.
